UNITED STATES PATENT OFFICE.

MARTIN J. C. A. MAURER, OF COWLING, ILLINOIS.

AUTOMATIC GATE.

1,324,127.

Specification of Letters Patent.

Patented Dec. 9, 1919.

Application filed December 23, 1918. Serial No. 268,064.

To all whom it may concern:

Be it known that I, MARTIN J. C. A. MAURER, a citizen of the United States, residing at Cowling, in the county of Wabash 5 and State of Illinois, have invented certain new and useful Improvements in Automatic Gates, of which the following is a specification.

This invention relates to an improvement 10 in farm gates or the like, and is more particularly directed to a means whereby the gate may be automatically opened and closed through actuation of elements by the vehicle in the travel of the latter to, through, 15 and beyond the gateway.

In automatic gates of this type it is customary for the vehicle to actuate a trip by which the gate is released to the influence of a spring or weight for opening the gate, 20 said gate being either manually closed after such opening, or complicated mechanism to this end being provided.

It is the object of the present invention to both open and close the gate through the use 25 of weights, to thereby insure constant and uniform efficiency, the closing weight being set for operation in the travel of the vehicle through the gate way, and being sufficient to both close the gate and reset the gate-opening 30 weight.

An important detail of the present invention is the provision of means whereby the vehicle operates to simply reset the gate-closing weight, without complication of 35 other operating parts, so that the closing weight in operation, after resetting, is called upon to perform the function of closing the gate and resetting the gate-opening weight.

The invention is illustrated in the accompanying drawings, in which:—

Figure 1 is a perspective view showing the improved gate structure, the normally concealed parts being indicated in dotted lines.

Fig. 2 is a broken plan of the gate and operating means therefor.

Fig. 3 is a vertical sectional view through the operating means.

Fig. 4 is a perspective of the weight means, the connections therefrom and to the clutch being particularly shown.

Fig. 5 is a perspective view showing more particularly the vehicle-operated means for resetting the gate-closing weight.

Fig. 6 is a sectional view, partly in plan, of the same.

The improved automatic gate structure, as here shown, comprises a gate proper, as 1, which aside from the details hereinafter described may be of any desired form or construction. The gate is preferably mounted on roller supports 2, adapted for travel on a suitably constructed track 3. A housing 4 for the operating means is arranged at one side of and adjacent the rear of the gate when the latter is in its closed position. This housing is in the form of a box-like structure, closed on all sides to protect the operating parts.

A shaft 5 is mounted in and transversely of the housing, on which adjacent one side wall of the housing is loosely mounted a gate-operating wheel 6. This wheel is peripherally grooved, as at 7, to receive a cable 8, adapted to be wound about the wheel, the respective ends of the cable extending in opposite directions from the wheel, through openings in the end walls of the housing, and terminally connected to arms 9 and 10, secured at the respective ends of a bar 11, fixed to the upper rail of the gate. The bar 11 is of sufficient length to maintain the arm 9 forward of the housing and the arm 10 rearward there at all times, such bar being thus considerably longer than the gate, as shown in Fig. 1. As the cable 8 is wound about the wheel 6, and connected to the respective arms 9 and 10, it is apparent that the gate may be moved in either direction by properly turning the wheel.

Secured to or preferably formed integral with the wheel 6 is a pulley 12, about which is wound an opening cable 13, which cable beyond the pulley 12, passes through an opening in the rear wall of the housing, and extends over a guide pulley 14, supported in a frame 15, fixed to the housing, and is terminally provided with a weight 16. The cable 13 is so wound about the pulley 12 that, under the influence of the weight 16, when free to act, the wheel 6, will be turned in a direction to draw upon the cable 8 to open the gate, as will be plain from Fig. 1.

A sheave 17 is fixed on the shaft 5, adjacent the wheel 6, and peripherally formed with two cable-receiving channels 18 and 19. Secured to the sheave 17 and wound about one of the channels, as 18, is a gate-closing cable 20, which extends through an opening in the rear wall of the housing, and over a guide roller 21, mounted in a frame 22, fixed to the housing. The free terminal of the

cable 20 has connected thereto a weight 23, which is considerably heavier than the weight 16, and which weight is sufficient to not only move the gate to closed position, but 5 also elevate the weight 16. The cable 20 is of course so wound about the sheave 17 that when the weight 23 is free to act the wheel 6 will be turned in the proper direction to close the gate.

10 It is apparent, however, that means must be provided for so controlling the gate closing weight 23 that such is without influence on the gate during the opening operation, and yet so that such weight 23 may be given 15 control when necessary to close the gate and reset the gate opening weight.

To secure this result, there is provided a clutch connection between the sheave 17 and wheel 6, and means for controlling this 20 clutch connection in the operation of the gate-closing weight. The clutch comprises a series of pins 24, slidably mounted in the sheave 17, and terminally formed as teeth to coöperate with teeth 25 on the face of 25 the wheel 6. The pins are connected to a collar 26, slidably mounted on the shaft 5, and peripherally grooved to receive an adjusting yoke 27, connected to a lever 28, pivotally supported in the housing. The free 30 end of the lever extends through the top of the housing, and is connected to a cord 29, led over guide pulleys 30, to a trip-plate 31, pivotally supported in frame 22. The closing weight cable 20 passes through the trip- 35 plate 31, and is provided at an appropriate point with a stop 32, which engages and operates the trip-plate to move the lever 28 to free the clutch, under circumstances which will later appear.

40 The gate is held in both open and closed positions against the influence of any moving means, by what may be termed a gate latch 33, formed as a weight slidably mounted in an upright frame 34 constructed as a post extending into the ground on one side of the gate and an additional post rising from the housing 4. The weight of the gate latch is provided with a roller 35 for engagement with the rod 11, when the gate is 45 moving, to avoid undue friction. The gate proper is provided with a stop 36 at the rear end, behind which the latch is engaged to hold the gate in closed position, and the 50 bar 11 terminates at the forward end above a projecting shelf, forming a stop 37, in front of which the latch engages to hold the gate in open position.

The latch 33 is connected by a cable 38, leading over guide pulleys 39 on a frame 40, 60 secured on the frame 34, and thence through a conduit 41 extending substantially in the plane of the gate from the housing 4 to the center of the roadway. At the forward end, the conduit 41 communicates with a conduit 42, extending longitudinally of the

roadway, and to a point a predetermined distance beyond the gate in both directions. The terminals of the conduit 42 are enlarged and their tops are slotted to permit the projection therethrough of trip levers 43, pivotally mounted in the enlarged portions of 70 the conduit. The trip levers 43 are connected by cables 44 to the cable 38, suitable guide pulleys being employed, so that movement of either trip lever 43 will elevate the 75 latch 33 from the stop 36 or 37, as the case may be to release the gate.

The conduit 42 is centrally provided with a depending portion 45, and the top of such conduit above the depending portion is longitudinally slotted, as at 46. A guide block 47 is arranged in the depending portion 45 of the conduit, with its ends inclining downwardly and outwardly, as at 48. A resetting member 49 is mounted for sliding movement on the block 47, and comprises a trip-lever 50, mounted on a base having spaced rollers 51 for travel on the upper surface of the block, and bearing arms 52 projecting in both directions from the base, and having a single terminal supporting roller 53. The resetting member 49 is connected to a resetting cable 54, which leads over guide pulleys 55 to the housing, and is there wound about the sheave 17, in the channel 95 19. This cable 54 is so wound about the sheave that when drawn upon, the cable 20 will be wound upon said sheave, to raise the weight 23.

As the parts are arranged in Fig. 1, the 100 gate is closed, the opening weight 16 elevated, and the closing weight 23 lowered. If an advancing vehicle engages one of the trip levers 43, as by the vehicle axle, the 105 cables 44 and 38 are drawn upon, and the latch 33 raised to release the gate. The weight 16, through the cable 13, operates the wheel 6, which is moved in the proper direction to cause the cable 8 to open the gate. When the gate is opened, the latch 33 110 engages the forward stop 37, and the gate is held open. The vehicle in moving through the gateway, engages the lever 50 of the resetting member, and through cable 54, the movement of the resetting member longitudinally of the block 47, will wind the cable 20 on the sheave 17, thus raising the gate closing weight 23. The movement of the resetting member under the action of the vehicle continues until the rollers 51 engage 115 120 stops 56 on the ends of the block, in which position the then forwardly extending arm 52 will ride down the inclined end of the block, to permit the lever 50 to tilt, and so free itself from the vehicle engaging portion. The vehicle in continued travel engages the other trip lever 43, again raises 125 the latch and frees the gate to the influence of the weight 23, by which the gate is closed. In this operative movement of the weight 130

23, the clutch pins 24 are in operative function, so that the wheel 6 is turned in the proper direction to close the gate, and the cable 13 drawn upon to raise the weight 16. 5 The weight 23 thus closes the gate and resets the opening weight.

As the cable of the gate closing weight reaches a predetermined position, that is with the weight in practically its lowered 10 position, the stop 32 engages and operates the trip-plate 31, to thereby open the clutch as previously described. The parts are held thus to prevent interference with the subsequent gate opening operation, and the clutch 15 will not again function until the resetting member 49 is operated to elevate the closing weight 23.

It will be understood that the gate can be opened or closed by a vehicle moving in 20 either direction, and that the gate closing operation, even though the weight 23 is set as the vehicle moves through the gateway, will not take place until the latch is released by the remote or final trip 43. The conduits 25 41 and 42 are preferably set in the ground, with their top sections flush or substantially flush with the ground surface.

Having thus described the invention, what is claimed as new, is:—

30 1. A gate, an opening weight, a closing weight, and a clutch controlled by the closing weight for permitting the movement of the closing weight to restore the opening weight.

35 2. A gate, a closing weight, a restoring member connected to said weight, an opening weight, a gate operating wheel under the influence of the opening weight, and means whereby the closing weight is automatically 40 connected to said wheel when said weight is in predetermined position.

3. A gate, an operating wheel therefor, an opening weight connected with said wheel, a closing weight, vehicle operated means for 45 raising the closing weight to effective position, and a clutch controlled by said closing weight for connecting the latter to said wheel.

4. A gate, opening and closing weights 50 therefor, the closing weight being heavier

than the opening weight and serving to raise the opening weight to effective position when closing the gate, and vehicle operated means for raising the closing weight to effective position.

55

5. A gate, an operating wheel, a cable connecting said wheel and gate for operation of the gate in either direction, a closing weight, a sheave connected to said closing weight, a clutch between said sheave and wheel, means for opening said clutch when the closing weight has operated to close the gate, and means for holding the clutch in function during the gate closing movement of said closing weight.

65

6. A gate, an operating wheel therefor, an opening weight, a closing weight sufficient to close the gate and restore the opening weight to effective position, a latch, stops on the gate to be engaged by the latch 70 to hold the gate open and closed, roadway trips to release the latch, and a roadway member operable to raise the closing weight to effective position.

70

7. A gate, an operating wheel therefor, an opening weight, a closing weight, a roadway member operable to raise the closing weight during the gate closing movement of such 80 closing weight, means to use the influence of the closing weight to raise the opening weight during the gate closing movement of such closing weight, means to disconnect the closing weight and opening weight when the closing weight has reached a predetermined lowered position, and trip-controlled gate latches for the gate.

85

8. A gate, an operating wheel, a cable connecting said wheel and gate, an opening weight connected with said wheel, a sheave arranged adjacent the wheel, a closing weight carrying cable wound about said sheave and operable to raise the closing weight to effective position, a roadway member connected by cable to said sheave, a clutch between the wheel and sheave, and a trip operated by the closing weight cable 90 and connected to the clutch to open the clutch when the closing weight has reached a predetermined lowered position.

90

In testimony whereof I affix my signature.
MARTIN J. C. A. MAURER.
